GUSTAVE ADOLPH NEW, OF PORT CLINTON, OHIO, ASSIGNOR TO THE AMERICAN GYPSUM CO., OF PORT CLINTON, OHIO, A CORPORATION OF OHIO

HEAT INSULATING AND ACOUSTIC PLASTER

Application filed October 4, 1930. Serial No. 486,359

This invention relates to a heat insulating and acoustic plaster which has for its purpose to provide a plaster composition which will combine sound-absorbing and heat and cold insulating qualities.

The demand for acoustic plaster is becoming greater every day. Such plaster is applied over various surfaces, such as plaster-board, etc., but generally over a so-called brown plaster coat. This brown coat consists of a mixture of approximately 25 parts of gypsum plaster and 75 parts of sand with a little fibre and retarder. Inasmuch as a wall made of this material is very dense and hard, it has very little insulating qualities against heat and cold. If acoustic plaster is applied over same— $\frac{1}{2}$ inch thick as a rule, the sound-absorbing coefficient is derived from this application itself and lowered on account of the hardness or density of the underlaying base coat. The coefficient, however, is greatly increased if the base coat is of a sound-absorbing nature in which it renders a two-fold purpose; increased sound-absorbing coefficient as well as insulating values.

To accomplish this, I mix with the gypsum stucco, instead of sand, a sufficient amount of a heat and cold resisting soft and porous material such as zonolite or Rockwool, etc.

Zonolite is a granular, very light material weighing only 8 pounds per cubic foot and it mixes well with stucco. It is a non-metallic mineral composed of silica, magnesia and alumina, found in Montana, and used for heat insulating. On account of its bulk and smooth surface the spreading or covering capacity is greatly increased over the sanded plaster and it works considerable more free under the trowel.

After the material (this base coat) is dry, it is not only sufficiently hard, but porous enough to make it an ideal insulator.

On account of the great bulk of zonolite, the amount—weight—over sand in this base coat has to be reduced considerably, making this material also very economical.

The principal idea in this development lies in the combination of an insulating plaster, as a base coat and acoustic plaster as a finish coat, but this insulating base coat may be

used also in connection with any other top or finish coat, such as lime putty, etc. since the insulating plaster described has sound-absorbing qualities.

For purpose of illustration, Fig. 1 shows a plan view of the plaster and Fig. 2 is a section.

In these drawings, 6 indicates the base coat which as stated consists of a mixture of gypsum and zonolite or similar material of granular and somewhat fibrous quality having the form of small particles or shreds which make the coating sufficiently porous to have heat insulating and also somewhat sound-absorbing qualities. Upon this is applied the outer or face coating of so-called acoustic plaster indicated at 7 which may be any of the known compositions for this purpose, being somewhat soft and chalky in quality and having its surface broken by a multiplicity of fine depressions or interstices indicated at 8, which may be produced by a proper tool or implement and which gives it the sound-absorbing quality characterized by the term acoustic plaster.

The combination of the two coats produces a plaster or wall covering having both heat insulating and sound-absorbing qualities to a great extent.

I claim:

1. A plaster comprising a base coat of gypsum stucco mixed with soft and porous heat insulating material, and a finish coat of sound-absorbing material.

2. A combined heat-insulating and sound-absorbing plaster comprising a base coat of gypsum stucco mixed with heat insulating and sound absorbing fibrous material, and a finish coat having sound-absorbing interstices.

In testimony whereof, I do affix my signature.

GUSTAVE ADOLPH NEW.
